Inventor.

Charles Pettibone

UNITED STATES PATENT OFFICE.

CHARLES PETTIBONE, OF CHICAGO, ILLINOIS.

DESIGN FOR A BADGE.

SPECIFICATION forming part of Design No. 21,886, dated October 11, 1892.

Application filed August 27, 1892. Serial No. 444,318. Term of patent 3½ years.

To all whom it may concern:

Be it known that I, CHARLES PETTIBONE, a citizen of the United States, residing at Chicago, in the county of Cook and State of Illinois, have invented and produced a new and original Design for a Badge, of which design the following is a specification, reference being had to the accompanying drawing, forming part thereof.

- 10 The leading or characteristic features of the design are a starred and striped flag depending from a bar which is surmounted by an eagle with spread wings grasping a cluster of arrows in its talons and having upon the striped face of said flag, centrally disposed, a circular field carrying a representation of a man kneeling upon the shore with a flag in his hand, with other figures, as of spectators, at the side foreground and ships in the background, the same being a conventional representation of Columbus taking possession of the newly-discovered lands of North America, the whole being concluded with a plain panel

extending from the striped end of the flag, upon which a suitable inscription may be placed.

In the figure of drawing, A represents the spread-eagle; B, the flag vertically depending therefrom and having thirteen stripes of contrasting colors with a field of forty-four stars 30 in the upper right-hand corner; C, the field, circular in outline, surrounded by a plain name-panel, within the interior of which is set the representation of the landing scene, while D represents the plain panel with which 35 the badge terminates.

Having thus described my design, what I claim, and desire to secure by Letters Patent of the United States, is—

The design for a badge, as shown and described.

CHARLES PETTIBONE.
